CLAIM

The ornamental design for a billiard bridge, as shown as described.

DESCRIPTION

FIG. 1 is a perspective view of a billiard bridge showing my new design in use condition;

FIG. 2 is a perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken line showing of a pool stick and cue balls in FIG. 1 is included for the purpose of illustrating environmental structure and forms no part of the claimed design.

1 Claim, 3 Drawing Sheets
